UNITED STATES PATENT OFFICE.

CHRISTINE ZIBULSKI, OF MUNICH, GERMANY.

ADJUSTABLE ARM-REST.

SPECIFICATION forming part of Letters Patent No. 711,550, dated October 21, 1902.

Application filed March 16, 1900. Serial No. 9,002. (No model.)

To all whom it may concern:

Be it known that I, CHRISTINE ZIBULSKI, widow, *née* ARNOLD, a subject of the Emperor of Germany, residing at Munich, in the 5 Kingdom of Bavaria, Germany, have invented certain new and useful Improvements in Adjustable Arm-Rests, of which the following is a full, clear, and exact description.

My invention relates to means whereby in 10 operating upon or treating the arm of the human body a support may be furnished which is adjustable to suit all the different positions in which the physician may find it necessary to have the arm fixed; and my invention consists in the features and combinations of parts hereinafter fully described, and particularly pointed out in the claim.

In the accompanying drawings, Figure 1 represents a vertical sectional view of the apparatus with parts in elevation. Fig. 2 is a plan view of a section on the line A B of Fig. 1. Fig. 3 is a detail plan view of a supporting-arm and attached devices. Fig. 4 is a detail view of the arm-rest. Fig. 5 is a detail view, partly in section, of a detail part of the mechanism. Fig. 6 is a front view, partly in section, of Fig. 5.

The apparatus is supported upon a plate *a*. At one end of this plate is located a vertically-channeled support *e*, the edges of which are toothed, as at *e*^x in Figs. 1 to 5. An arm *l* is adapted to slide vertically in this guide-way and may be supported at any desired height by a catch-lever *f*, having a pin to 30 engage the teeth *e*^x, said catch-lever being pressed normally into engagement with the teeth of the channeled bar by a spring *y*. The bar *l* carries at its upper end a shoulder-rest *k*. The base-plate *a* is provided with a 35 curved channel *c*', forming a segment of a circle, and it is also provided with a channel or slot *c*², radiating from the center from which the slot or channel *c*' is struck. In the channel *c*² a clamping-bolt *x* is adjustably ar- 40 ranged to hold an arm *t* in different positions in relation to the vertical channel *e*. The arm *t* is jointed by means of a bolt *x'* to a section *t'*, with which it has a sliding connection. For this purpose the bolt *x'* passes 45 through a slot *x''* in the part *t'*. The arm *t'* in turn is jointed by means of a bolt *x*² to an arm *t*², so that said arm *t*² may have pivotal adjustment in relation to the arms *t* and *t'*. The arm or section *t*² has a bolt *x*³ passing 50 through a slot thereof, the head of the same,

*x*⁴, as shown in Fig. 1, being arranged to bear against the under side of the overhanging flanges *c*^x, forming the top of the channel or way *c*'.

By means of the slot *x*⁵, through which the bolt *x*³ passes, it will be seen that the arm *t*² can be adjusted, as shown in dotted lines in Fig. 2. Each of the sections *t* *t'* *t*² has an arm extending vertically therefrom, (marked, respectively, *p*, *q*, and *r*.) These arms are slot- 60 ted, and through these slots bolts *x*⁶ *x*⁷ *x*⁸ pass, said bolts being connected, respectively, with standards *m* *n* *n'* *o*, extending down, respectively, from the sections *m*, *n*, and *o* of the arm-rest. By means of the bolts *x*⁶ *x*⁷ *x*⁸, 70 which have suitable wing-nuts, the arm-rest may be adjusted vertically as desired. The section *n* is hinged at *n*² to the section *m* of the arm-rest, so as to have vertical adjustment, as shown in dotted lines in Fig. 1, and 75 the section *o* is pivoted at *x*⁹ to the section *n*, so that it may be adjusted horizontally at an inclination to the sections *m* and *n*, as shown in dotted lines in the plan view Fig. 3. To the under side of the section *m* of the arm- 80 rest arms *h* are secured, extending toward the standard *e*, said arms being slotted for the passage of a clamping-bolt *x*¹⁰. This bolt passes through the slot of an arm *f*', secured to the support post or standard *l* of the shoulder-bolster *k*. The lower end of this slotted arm is connected to a link *g*.

By means of the described joints and connections of the various parts it will be seen that the arm-rest may be adjusted to various 90 positions to suit the requirements of the operations to be performed.

I claim as my invention—

Supporting means for the human arm comprising sections *m*, *n* and *o*, adjustable supports *p*, *q* and *r* connected thereto, a base-plate having a circular and a straight slot therein, the arms or sections *t*, *t'*, *t*², adjustably connected together and adjustably mounted in the said slots, the said supports *p*, *q*, *r*, being connected with the sections or arms *t*, *t'*, *t*² and a bolster *k* with means for supporting the same adjustably, substantially as described.

In witness whereof I subscribe my signature in presence of two witnesses.

CHRISTINE ZIBULSKI.
